FILLER FORMER FOR CIGAR MACHINES

Hjalmar E. Carlson, Brooklyn, N. Y., assignor to
 International Cigar Machinery Company, a corporation of New Jersey

Application June 12, 1937, Serial No. 147,916

20 Claims. (Cl. 131—40)

This invention relates to cigar machines, and more particularly to a method of feeding long filler tobacco and an improved and simplified filler feeding mechanism therefor.

Usually when feeding long filler tobacco into charge forming mechanism, the operator places the leaves in a feed channel and forms therein by constant addition thereto a continuous stream of long filler tobacco which is advanced past cutters which sever bunch length sections therefrom; these sections are then passed on to other tobacco handling instrumentalities and suitable bunch charges are made and transferred to bunch rolling mechanism. In feeding tobacco in this manner the operator must endeavor to keep the tobacco in the stream up to a certain level, and not feed to much or too little lest the resulting bunch charges reflect these variations and be overheavy or underweight.

According to the present invention, an operator feeds tobacco in usual manner to form a continuous stream, but it is relatively unimportant if she overfeeds. In fact she may overfeed without any danger of the resulting bunches being overheavy since automatically acting mechanism is provided for limiting the stream passing to the bunch length cutters to uniform thickness and density. From this it follows that operators feeding tobacco in this machine need not be highly skilled in order to feed long filler tobacco satisfactorily. Also, due to the fact that the machine of this invention forms bunch charges of long filler tobacco of uniform size, thickness and density in a simplified manner, and cuts the tobacco only once, the possibility of forming undesired scrap, which is often produced when several cuts are needed to form a bunch charge, is held to a minimum, and hence better bunches and more satisfactory long filler cigars result. Furthermore, the formation of measured bunch charges in the feed mechanism of the cigar machine results in a simpler machine, and eliminates many machine parts heretofore necessary to produce bunch charges.

It is an object of this invention therefore to provide a method of feeding and a long filler tobacco feed mechanism for a cigar machine in which cigar bunch charges of substantially uniform size and density are produced with a minimum of cutting.

It is a further object to provide a method of feeding and a feeding mechanism having devices for forwarding a continuous stream of long filler tobacco, and means for automatically reducing the stream to uniform thickness and density as

it travels to the cigar bunch length forming mechanism.

The invention also consists in the provision of automatically acting means for advancing a continuous stream of tobacco past compressing and trimming devices which compact the stream to a substantially uniform density, remove the excess from the stream and automatically redirect it back for association with later fed tobacco.

10 The invention also contemplates the provision of bunch forming mechanism of a simplified nature in which the skill of the operator feeding leaves to the advancing means has relatively little effect upon the finished cigar, especially insofar as overfeeding is concerned.

15 In the feeding of tobacco in this machine the stream of tobacco has been reduced to the predetermined size, thickness and density before it is fed to the bunch length cutter, and the resulting bunch lengths are each ejected onto the rolling apron for formation into bunches. It is evident, therefore, that no accumulating errors of size or density can creep into the bunch length due to the association of several lengths which 20 may be of varying weight and density, and the severance of a bunch charge from the leading end of the assembly. The invention, therefore, includes means for forming uniform bunch charges from an advancing stream of tobacco by 25 a single severing operation, and the formation of bunches from successive individual charges transferred from said means to the rolling mechanism.

30 35 In addition to the mechanism which has been provided for automatically removing excess tobacco from the top of the stream and returning it to the source for further feeding, there is also contemplated means for signalling when insufficient tobacco is being fed in order to notify the operator so that she may bring the quantity to be fed up to the requisite amount before a number of bunch charge increments have been fed through the feed mechanism to do much harm 40 in the production of non-uniform bunches.

45 50 With these and other objects not specifically mentioned, in view, the invention consists of certain constructions and combinations which will be hereinafter fully described, and then set forth more specifically in the claims.

In the accompanying drawings wherein is shown one of the various possible embodiments of this invention, which form a part of this specification, and in which like characters of reference indicate the same or like parts:

Fig. 1 is a schematic plan view of the filler feed;

Fig. 2 is a side view partly in section showing details of the compactor and the knife and return chute;

Fig. 3 is a plan view of Fig. 2;

Fig. 4 is a sectional end view of one of the compactors;

Fig. 4a is a partial detail side elevation of the compacting mechanism and stream testing device;

Fig. 5 is an end view of the knife actuating mechanism;

Figs. 6 and 7 are detail fragmentary views illustrating certain parts of the device shown in Fig. 1, but in different positions;

Fig. 8 is a sectional view taken on line 8—8 of Fig. 1;

Fig. 9 is a sectional view of Fig. 1 taken on line 9—9; and

Fig. 10 is a sectional view taken on line 10—10 of Fig. 1 showing the bunch charge cutting mechanism.

The filler tobacco is placed into the filler feeding channel formed by the horizontal feed belt 10 and the two vertical feed belts 11 and 12, this channel forming the feed for filler tobacco similar to that shown in the patent to Bronander, 1,740,571, granted December 24, 1929. The horizontal belt 10 is supported upon a plate S of a width substantially that of the belt, and may be driven in the same manner as disclosed in the above patent. The vertical belts 11 and 12 are supported in tobacco engaging position by pulleys 13 and 14, and pulleys 15 and 16, respectively. The belts 11 and 12 are also led around suitable guide rollers 110 of well-known design and arrangement suitably mounted on the machine table B and the belts are formed into tightening loops about these last-named rollers. The belts, mentioned above which form the feeding channel, are intermittently driven by suitable means such as disclosed in the above-mentioned patent to Bronander.

In a device such as shown by Bronander, bunch lengths cut from the advancing stream are not complete and ready for rolling with binders into bunches. Instead, lengths are pushed laterally into juxtaposition with previously cut lengths, compacted to proper density, and charges are cut from the leading edge of the grouped lengths. This cutting naturally results in the formation of some scrap particles, which are unwanted in long filler cigars. According to the structure shown in Figs. 1, 2 and 3 all of the operations necessary to produce bunch charges of proper size, thickness and density are effected in the feed mechanism; the bunch charge is cut only once, thereby practically eliminating the formation of small pieces and the mechanism employed is simpler by many parts.

The filler tobacco progressively placed in the filler feed channel formed by the belts 10, 11 and 12, is intermittently advanced and passes in a stream of varying thickness and density under a guide 17 located to direct it beneath compactor 18, which in the illustrated embodiment consists of a wheel 18 mounted upon a shaft 19. A sprocket 20 fixed on the end of shaft 19 is suitably driven, by a conventional chain drive not shown, from the driving means of pulley 15.

The compactor wheel 18 is provided with a series of spaced, radial holes 21, Fig. 2, each of which receives a shank 22 of the several plungers or compactors 23. The shank 22 of each

plunger supports a stud 24, equipped with a cam follower 25 adapted to engage the inner periphery of an adjustable stationary cam 26. This cam is mounted on bracket 26c, which is provided with a semicircular extension 26a upon which the cam 26 may be moved circumferentially in order to position the lowermost portion 26b of the cam in the proper location for best results. Adjustments are effected by means of openings and screws respectively formed in and carried by the cam and semicircular bracket extension 26a. While several means may be utilized for resiliently supporting the compacting faces 23 in the wheel 18, it has been found that their shanks may be mounted in holes 21 and forced outward by springs 27. Thus as the cam followers move off the high part of the cam 26 springs 27 will force the compactors into contact with the advancing stream of tobacco and compress it to the predetermined density. It is obvious that weights or other cam controls could be utilized for this same purpose. It is apparent that there can be no positive crushing force applied to break up the tobacco and at the same time the density of the layer treated by the compacting device will be substantially uniform because of the operation of compactors 23 and the setting of the wheel 18. Variations in density of the layer passing to the bunch charge severing cutter are extremely unlikely. Each compactor 23 is continuously pressed by its respective spring 27 outward against the tobacco stream, which stream is thereby brought to proper density and so held. The compactors 23 do not recede or rise until their control cam followers 25 ride up on cam 26 again following the cutting operation of knife 30.

In order to change the compressive force of the compactors 23 and vary the density of the stream, shaft 19 is vertically adjustably mounted in bracket 26c which is suitably fixed to the bed B. This shaft is journaled for rotation in an adjustable block 26e slidably in slot 26d of bracket 26c. The required adjustments are made by turning screw 26f right or left to raise or lower block 26e. Lock nut 26g holds the screw 26f in adjusted position.

In order to form a layer of tobacco of proper thickness a knife 30 is mounted in the path of the filler tobacco stream usually with its cutting edge beyond the vertical plane through the axis of the compactor wheel 18, and is operated to sever the excess tobacco from the main body of the stream. A straight knife is preferred because it can be placed nearer to the compactors when the tobacco is under maximum compression than can any other type of knife and hence the density of the charges being formed is more accurate. A chute 31 is located proximate the knife and deflects the excess which has been removed back to the source. As shown, chute 31 discharges onto a belt 32 which returns the tobacco to the feeding channel, in a manner to be latter described. The chute is mounted for vertical adjustment so that the plane of the lip adjacent knife 30 may always be coincident therewith. In the embodiment shown, brackets 31a are fixed to table S and are provided with elongated slots 31d through which pass bolts 31c projected through the bent ends of a bar 31b secured to the underside of chute 31. Wing nuts 31e on bolts 31c secure the chute in adjusted position. The tobacco passing under the knife 30 is now of uniform density and correct size and thickness to make the bunch, this layer

of tobacco being advanced forward and acted upon by a corrugated cutter 33 which may be of the type shown in the Bronander patent above referred to (Fig. 1) which severs a length from the layer of tobacco to produce a complete bunch. In the illustrated form, knife 30 comprises a reciprocating serrated edged blade which is adjustably mounted in order to provide means for varying the thickness of the layer advanced to the cutter 33.

The shaft 35, of motor 36, Fig. 1, is equipped with an actuator 37 carrying a crank pin 38 on which is loosely mounted a link 39 connecting to one end of an arm 40 fulcrumed at 41 in a bracket 41b mounted upon bed B, Figs. 5 and 8. The lower end of arm 40 has a slot 42 engaging a pin 43 carried by an arm 44 integral with the U-shaped frame 45. Arm 44 together with arm 46, which is also part of frame 45, carries the knife 30, Fig. 1. Blocks 47 and 48 which support and guide the arms 44 and 46 in their to and fro motion are adjustably mounted on the bed B in order to provide for adjusting knife 30 vertically to vary the thickness of the tobacco stream passing to the bunch cutting device. Fig. 1 shows the adjustments generally, whereas Fig. 5 shows them in detail, although as applied only to one block since the construction of block 48 is identical only one will be described. Block 47 is mounted on a bracket 47a fixed to the bed B, and is furnished with an elongated slot 47c through which projects a screw 47b carried by bracket 47a. A wing nut 47d holds the assembly in adjusted position.

The filler tobacco on reaching the charge forming corrugated cutter 33 is acted upon by a plate 50, Fig. 1, which compresses the tobacco and retains its position while the cutter 33 severs a bunch length from the filler layer. Plate 50 is suspended from a rod 51 slidably mounted in a lug 52 of cutter bracket 53. A compression spring 51a arrested between the lug and plate tends to normally hold nuts 51b threaded on rod 51 against lug 52. The charge having been cut, now rests on the cutter platform 55 which then descends, whereupon a pusher 56, suitably operated, as shown in the Bronander patent mentioned above, passes over the platform and delivers the charge onto the rolling apron 57. In the meantime the cutter bracket 53 ascends carrying the cutter 33 and plate 50 from the filler layer.

Fig. 6 illustrates one way in which complete bunch charges may be forwarded directly to bunch forming mechanism and comprises the platform 58 and follower 59 shown in the position they occupy when a charge has just been moved from the cutter platform 55 on to the rolling apron 57 overlying the platform 58. The platform and follower then move downward, by means similar to those disclosed in the patent to Bronander, No. 1,563,333, granted December 1, 1925, the follower moving at a greater rate of speed than the platform in order to overtake the charge being lowered before the platform reaches its lowermost position. As the platform approaches the end of its downward movement, the loop is formed in the rolling apron, and the lower edge of the follower 59 engages the charge C to one side of its mid-section. A little further, downward movement of its parts results in spreading or fanning out the leaves of the charge C and in simultaneously converting said charge from its initial substantially flat form to the arculate form as clearly shown in Fig. 7. As soon

as this is accomplished, the follower 59 is given a rapid upward movement so that the loop forming roller 60 can come into action and roll the charge.

5 The excess quantity of tobacco scalped from the main body of filler tobacco, Figs. 1, 2 and 3, passes up the inclined runway 61 and is directed into the chute 31 which leads the tobacco onto a conveyor 32 carrying the same onto a turn-table 62. The table 62 is provided with guides 63 and 64, tending to lead the tobacco into the feeding channel formed by belts 10, 11 and 12. In this manner, the scalped tobacco is returned to the belt 10 and the additional tobacco required for the filler is placed on top of the previously scalped tobacco.

10 In the operation of this machine, it is relatively unimportant if an excess of tobacco be fed to the feed channel since the compactor 18 and knife 30 always automatically reduce the stream passing to cutter 33 to uniform density and thickness, and chute 31 returns the excess back to the source for redistribution in the channel. However, if an insufficient quantity of tobacco is fed, it is necessary to signal the operator at 15 once in order that bunch lengths will not be formed which will result in the production of underweight cigars that will not pass inspection. In order to prevent this contingency a device has been provided for apprising the operator when less than the required amount of tobacco is being placed in the feed channel.

20 Referring to Fig. 2, it will be observed that when the tobacco stream is of proper thickness, cam followers 25 are held away from cam track 26b by the tobacco and compactors 23 are resiliently forced against the tobacco by springs 27. If, on the other hand, the stream content is 25 inadequate the cam followers will move out farther, and may engage the track 26b, in which case the compaction of the stream would not be that required, and bunches of varying density would result. For best results, therefore, the cam followers should not engage track 26b.

25 Referring to Figs. 4 and 4a, there is shown one form of device for preventing underfeed of filler tobacco to the channel. A bracket 610 is mounted upon shaft 19 and is adjustably fixed to bracket 26c. Bracket 610 is provided with two arms, 30 one of which carries a stud 63 on which are mounted a trip finger 62, and a suitably insulated contact 64 adapted to engage with a contact 67 fixed to stud 63 carried by the second arm. A light spring 65 holds the trip finger in contact with rollers 66 mounted on the studs that support the cam followers 25, so that whenever an insufficient supply of tobacco has been placed in the channel and in the rotation of the wheel 18, as followers 25 move off cam 26, springs 27 will force shanks 22 outward, thereby causing rollers 66 to swing finger 62 and bring contact arm 64 into engagement with contact 67 to close a circuit through battery 69, wires 70, and 71 connected to the contacts and ring a bell connected in series in said circuit. If desired, other signalling devices such as a light, etc., might be used with equal success.

35 The several means referred to may be varied in construction within the scope of the claims, for the particular device selected to illustrate the invention is but one of many possible concrete embodiments of the same. The invention is not, therefore, to be restricted to the precise details of the construction shown and described.

40 70 75 75 What is claimed is:

1. A cigar machine comprising a compressing mechanism for compressing an advancing stream of tobacco to substantially uniform density, including a rotary member, a plurality of presser elements carried thereby and successively engaging said stream, and means for cutting off a layer of said stream to reduce it to substantially uniform thickness while under the influence of said elements.
2. A cigar machine comprising means for advancing a stream of long filler tobacco, a compacting device provided with a yieldable tobacco engaging surface adapted to compact said stream to substantially uniform density, cutting mechanism for cutting off the top portions of said stream to reduce it to substantially uniform thickness, said mechanism including a reciprocating knife, and means for driving said knife to effect said cutting operation.
3. In a cigar machine, in combination, means for forwarding a continuous stream of long filler tobacco, mechanism for forming bunch charges from said stream in a single cutting operation, said mechanism including a compacting member having yieldable tobacco engaging elements for compacting said stream to substantial uniform density, vertically movable cutting means operable transversely to said stream for cutting bunch charges of tobacco therefrom, and means for advancing said charges directly into a bunch rolling device without reducing the tobacco content of said charge.
4. In a cigar machine, in combination, means for feeding a continuous stream of filler tobacco, mechanism having a progressively acting yielding tobacco engaging surface for compacting said stream to substantially uniform density, means for reducing said stream to substantially uniform thickness, and means for determining the absence of sufficient tobacco in said stream.
5. In a cigar machine, the combination with means for feeding a stream of filler tobacco, of traveling compacting mechanism for compacting said stream to substantially uniform density, means for cutting completed bunch charges from the stream, and means for signalling an under-feed of filler to said stream.
6. In a cigar filler feed mechanism, means for feeding filler tobacco, a device for compacting said tobacco during its travel to substantially uniform density, said device having a traveling surface, a plurality of yieldingly mounted compactors carried by said device, a cam normally holding said compactors away from said stream, and means for moving said surface to release said compactors for engagement with said stream.
7. Mechanism for feeding tobacco comprising means for advancing a stream of long filler tobacco, a member provided with a travelling surface located above said stream and arranged to compress said tobacco to substantially uniform density, said member having a plurality of relatively movable tobacco contacting elements, a bunch charge cutter, and a knife positioned in said stream adjacent said member for trimming excess tobacco from said stream and forming therefrom a continuous layer of tobacco of uniform thickness to be fed to said cutter.
8. In a cigar machine, the combination with a conveyor for advancing a continuous stream of tobacco, of mechanism for forming complete bunch charges therefrom, said mechanism including a compacting device provided with a plurality of relatively movable tobacco engaging surfaces for compressing tobacco in said stream to substantially uniform density, means for adjusting said device to vary the density of said compacted stream, and means for cutting bunch charges from said stream.
9. In a cigar machine, the combination with means for feeding a continuous stream of long filler tobacco, of means for compacting said stream to substantially uniform density, a bunch charge cutter, means for measuring the thickness of the stream to be advanced to said cutter, said measuring means comprising a knife placed in said stream for trimming off excess tobacco, and means located substantially in the plane of and at the rear of the cutting edge thereof for guiding said excess trimmed from said stream and returning it to said feeding means, and mechanism for determining when an insufficient quantity of tobacco is being fed to said stream.
10. In a cigar machine, the combination with means for feeding a continuous stream of long filler tobacco, of means for compacting said stream to substantially uniform density, a bunch charge cutter, means for measuring the thickness of the stream to be advanced to said cutter, said measuring means including a knife placed in said stream for trimming off excess tobacco, and mechanism for determining when an insufficient quantity of tobacco is being fed to said stream, said mechanism comprising a trip finger cooperating with said compacting means, an electric circuit, a signal device, and means associated with said finger for closing said circuit whenever the quantity of tobacco in said stream falls below a predetermined level.
11. In a cigar filler feed mechanism, means for feeding filler tobacco, a device for compacting said tobacco to substantially uniform density during its travel, said device comprising a traveling member, a plurality of compactors carried by said member, a cam normally holding said compactors away from said tobacco, said cam having a portion so constructed that said compactors may move into contact with said tobacco when said portion is reached during the travel of said member, and means for adjusting said cam to control the position of said portion.
12. In a cigar machine, the combination with a conveyor for advancing a stream of filler tobacco, of a device for compacting said stream to a substantially uniform density, mechanism for cutting the top portion of said compacted stream therefrom to reduce it to uniform thickness, said compacting device being provided with a yielding tobacco engaging surface, and means for positioning said device to engage and compress said stream at such a point with respect to said mechanism, that the compression exerted by said surface upon the stream of tobacco being fed beneath said compactor is at a maximum at the zone of cutting.
13. A cigar machine comprising mechanism for compacting a stream of tobacco to substantially uniform density, means adjacent the center of pressure of said compacting mechanism for severing the top portion of said compacted stream to reduce it to uniform cross-section, and means cooperating therewith for maintaining said reduced stream compacted subsequent to the operation of said severing means and automatically returning said trimmed off tobacco for automatic reintroduction into said stream.
14. In a cigar machine, in combination, a conveyor for advancing a stream of filler tobacco, a device provided with a plurality of individually movable compacting elements for compressing

said stream to a substantially uniform density, means located substantially adjacent the point of maximum compression and beneath said device for severing excess tobacco from the top of the said stream, vertically movable cutting means for cutting bunch lengths of full stream width from said stream with a single transverse cut while maintaining said stream cross section constant, and means for forming said lengths into bunches, including means for maintaining the tobacco content of each length constant following its severance from said stream.

15. In a cigar machine, in combination, a conveyor for advancing a stream of long filler tobacco, a device for compressing said stream to substantially uniform density, a cutter extending transversely across said stream for severing tobacco from the top of said stream to limit the stream to a predetermined thickness, means mounting said cutter for movement beneath said device with the cutting edge thereof lying substantially in line with the center of pressure of said device, vertically movable cutting means operable transversely of said stream to cut bunch lengths of full stream width from said stream while maintaining said stream cross section constant for forming said lengths into complete bunch units, means for maintaining the tobacco content of each unit constant following its severance from said stream, and means located adjacent the rear of said cutter and lying substantially in the plane thereof for automatically directing tobacco removed from said stream by said cutter back onto said conveyor.

16. In a cigar machine, the combination with a conveyor for advancing a stream of filler tobacco, of a tobacco compacting device, including means for mounting said device against bodily movement relative to said stream, and movable means carried by said device for engaging and compacting said stream of tobacco passing thereunder, mechanism for severing the top portion of the compacted stream to reduce it to uniform thickness, means lying substantially in the plane of and adjoining said mechanism for holding said stream upon said conveyor after severing, a vertically movable charge cutter, and means for moving said cutter transversely to said uniform stream for forming complete bunch charges of original stream width and bunch length.

17. In a cigar machine, in combination, means for forwarding a continuous substantially horizontal stream of long filler, mechanism for forming bunch charges from said stream, said mechanism including a compacting device, means for mounting said device against bodily movement to and from said stream, means carried by said device movable into engagement with said tobacco

to compact said tobacco, and means for removing excess tobacco from said stream.

18. In a cigar machine, the combination with a conveyor for advancing a substantially horizontal continuous stream of tobacco, of mechanism for forming bunch charges therefrom, said mechanism including a compacting device for compressing tobacco in said stream to substantially uniform density, supports mounting said device against movement relative to said stream, and compacting means carried by said device and movable into engagement with said stream; means for adjusting said device on said supports to and from said stream to control the density thereof, means for trimming said stream to form a continuous layer of predetermined thickness, and a vertically movable charge cutter operating transversely of said stream for cutting complete bunch charges of stream width and bunch length therefrom while maintaining the stream cross section constant.

19. In a cigar machine, the combination with means for feeding a continuous stream of long filler tobacco, of means for compacting said stream to substantially uniform density, a bunch charge cutter, means for measuring the thickness of the stream advancing to said cutter, said measuring means comprising a knife located in said stream and extending from side to side thereof beneath said compacting means with its cutting edge proximate the line of maximum pressure thereof for trimming off excess tobacco, means for reciprocating said knife, and means substantially coplanar with said knife for removing said excess from said stream, and returning it to said feeding means, while holding said stream of measured thickness upon said feeding means.

20. In a cigar machine, in combination, means for feeding a continuous stream of long filler tobacco, and mechanism for forming bunch charges from said stream, said mechanism comprising a compactor device for compacting said stream to substantially uniform density, means mounting said device against bodily movement to and from said stream during the operation of said feeding means, compacting means mounted on said device for movement relative thereto into and out of compressing engagement with said stream, a cutter mounted beneath said device, means for moving said cutter to remove excess tobacco from said stream, and means for controlling the movement of said compacting means in the direction of stream travel to apply the maximum compacting force to said stream closely adjacent the cutting edge of said knife.

HJALMAR E. CARLSON.
